UNITED STATES PATENT OFFICE.

LENA E. JARVIS, OF SAN FRANCISCO, CALIFORNIA.

ROTARY SPRAY-BURNER.

1,201,828.

Specification of Letters Patent. Patented Oct. 17, 1916.

Application filed May 17, 1916. Serial No. 98,056.

To all whom it may concern:

Be it known that I, LENA E. JARVIS, a citizen of the United States, residing in the city and county of San Francisco and State of California, have invented certain new and useful Improvements in Rotary Spray-Burners, of which the following is a specification.

The present invention relates to improvements in rotary spray burners for liquid fuel, such as crude oil, and has for its principal objects to provide an oil burner having an improved means at the nozzle end thereof which is capable of thoroughly mixing the air and fuel before the same is ejected and which causes the fuel to be in the form of a confined flame on leaving the apparatus; to provide an improved means for forcing the air for combustion under pressure and with a whirling motion through the discharge nozzle; to provide a simple, compact, and efficient apparatus which is capable of manufacture at little cost and which is adapted for use where an economical apparatus capable of generating the maximum heat units with the minimum of fuel is desired.

With the above mentioned and other objects in view the invention consists in the novel construction and combination of parts hereinafter described; illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention, reference is directed to the accompanying drawings, wherein—

Figure 1 is a view in side elevation, partly in section, of an embodiment of my invention, illustrating the motor, the mechanism for driving the pump, the shaft and rotary atomizer, the rotary fan and casing, the deflector cone, the cup and cone housing, and the auxiliary air inlet. Fig. 2 is a top plan view of the apparatus with the motor removed, illustrating more particularly the system of connections from the oil pump to the rotary burner shaft. Fig. 3 is a side elevation of the pump taken on line 3—3 of Fig. 2, disclosing the pump casing broken away. Fig. 4 is a sectional view taken on

line 4—4 of Fig. 1. Fig. 5 is a view in end elevation of the deflector cone illustrated in Fig. 4. Fig. 6 is a view in front elevation of the atomizing cup. Fig. 7 is a sectional view taken on line 7—7 of Fig. 1. Fig. 8 is a sectional view taken on line 8—8 of Fig. 1.

Referring more particularly to the several views of the drawings, wherein like characters of reference designate corresponding parts,—1 indicates a suitable base mounting at one end a circular fan casing 2 provided centrally of its rear wall 3 with an air inlet opening 4, in the center of which is supported by the webs 5 the bearing support 6. The fan casing is provided centrally of its front wall 7 with an outlet 8 over which is fitted a cup housing 9, the open end 10 of which projects into the fire box through an opening in the wall 11 thereof.

Secured to the outer face of the front wall 7 of the fan casing is the peripheral edge 12 of an auxiliary air inlet chamber 13, provided centrally of its front wall 14 with an outwardly projecting cone shaped extension 15 which surrounds the cup housing 9 in spaced relation, the outer surface of the extension lying flush with the surface 16 of the opening in the wall 11 of the fire box.

Extending through the bearing support 6 and supported by a suitable bearing 17 carried thereby is a suitable tubular shaft 18 which is horizontally disposed and the threaded outer end 19 of which projects into the cup housing 9 and carries on its outer end the atomizing cup 20 having the outwardly flaring inner wall 21. Pressed or otherwise secured in the cup at the outer end of the axially disposed bore 22 which communicates at its inner end with the channel in the shaft 18, is an atomizing disk 23 provided with a plurality of slots 24 passing therethrough in a direction oblique to the faces thereof, and each extending from the peripheral edge toward the center of the disk.

Secured to the tubular shaft 18 in rear of the base of the atomizing cup and adjustable longitudinally thereon is the circular deflector and agitator cup 25 which encloses the atomizing cup, as in Figs. 1 and 4 of the drawings.

The deflector and agitator cup is open at its forward end and the inner face of the

forward portion 26 of the side wall thereof is outwardly flared, as in Fig. 4, and the rearward portion 27 of the side wall converges from the rear wall 28 to a point 5 where it joins the forward portion 26. The diameter of the chamber at the point A, where the portions 26 and 27 connect, is slightly greater than the largest diameter of the atomizing cup. The rear wall 28 of 10 the deflector and agitator cup is formed with the air inlet openings 28' and the supporting walls 29 between said openings are beveled or inclined, as in Fig. 4, to create a counter-current of air or back pressure to 15 that created by the hereinafter described fan, when the two are rotated in the direction of the arrow—Fig. 5. The outer surface of the forward end of the cup 25 rests on a flange 30 formed on the cup housing 9 20 and said flange provides a bearing for the outer end of the cup 25 and prevents the air from passing into the fire box at a point between the cup housing 9 and the outer surface of the cup 25.

25 Rotatably carried by the shaft 18, and positioned in the fan casing, is a suitable fan or blower 32 provided with the radially disposed sector shaped channels 33 which open at their inner end adjacent the center 30 of the fan or blower in communication with the air inlet opening 4 and open at their outer ends on the periphery of the fan. The outer wall of the fan casing which is in spaced relation to the fan carries on its inner surface the radially disposed blades 34 which converge toward the outlet 7 in the front wall of the fan casing, and said blades are covered by a plate 35 which fits snugly over the hub 36 of the fan or blower and 35 terminates short of the outer ends of the blades 34. The blades 34 and cover 35 provide a direct channel for conducting the air current generated by the fan into the cup housing and also arrest all eddy currents in 40 the air, and by so doing increase the velocity thereof.

45 The shaft 18 extends at its rear through a suitable gear box 37 and is secured at its rear end to the motor shaft 38 which is rotated in the direction of the arrow by the action of the motor 39. The shaft 18 carries a suitable worm gear 40 and the shaft and gear are provided with registering openings or channels 42 through which the fuel oil 50 passes into the bore in the shaft. A thrust bearing 43 is interposed between one end of the worm gear 40 and the inner side of the gear box and suitable gaskets 41 prevent the oil from working out around the shaft 18.

55 The worm gear 40 drives a suitable gear 44 also positioned in the gear box and said gear 44 is carried by a shaft 45 which extends from the gear box to a suitable pump housing 46 where it mounts one of the members 60 65 47 of a gear pump, and when the shaft 18

is driven in the direction of the arrow—Fig. 1, operates the gear wheels of the pump in the direction of the arrow—Fig. 3.

A fuel oil inlet 48 communicates with one side of the pump housing 46 and an outlet 49 extends from the opposite side of said housing and through the same the oil is pumped under pressure into a connection 50 which communicates with the gear box through the removable cover 51 thereof. The connection 50 is provided with the usual automatically controlled valve 52 and the manually controlled valve 53. A branch connection 54 leads from the connection 50 intermediate the pump and valve 52 and communicates through a relief valve 55 with the fuel supply.

It will be apparent by the present construction that I provide a direct drive from the motor to the fan, atomizer and deflector cup or cone and the rotation of the shaft causes the operation of the pump which supplies the fuel oil under pressure into the gear box to lubricate the pump drive gears and from where it passes into the tubular shaft.

The peripheral wall 12 of the auxiliary air inlet chamber is provided with the air inlet openings 56 which are controlled by the movement of the ported ring 57 slidably mounted within the chamber and which is operated through the handle 58. The oil being forced through the tubular shaft under pressure will enter the atomizing cone where it is thoroughly atomized, and owing to the rotation of the cone covers the inner surface thereof in a thin film. The rotation of the atomizing cup causes the thin film of fuel oil to pass into the fire box in a spray radially from the outer end thereof. The fan or blower which is operated by the rotation of the shaft generates an air current which enters the cup housing under great velocity, where it is acted on by the walls or blades 29 which are inclined in a direction reverse to the entering air current, and which set up a back pressure to reduce the swirling or rotary action of the air and cause the same to pass in a stream of approximately even velocity between the outer surface of the atomizing cone and the deflector cup. The action of the air stream issuing from between the atomizing cone and deflector cup is to cone or cup the oil spray, which owing to the velocity of the atomizing cup leaves the discharge end thereof in a radial path. Should additional air be required for combustion over that delivered by the fan, the ring 57 may be adjusted to admit the required air through the auxiliary air inlet ports. By adjusting the deflector cone relatively to the atomizing cup the shape of the flame may be regulated, as this adjustment controls the volume of air passing between the atomizing cup and

deflecting cone and causes the air to act directly on the oil film passing radially from the atomizing cup.

Having thus described my invention, 5 what I claim as new and desire to protect by Letters Patent is:—

1. A rotary spray burner comprising a rotatably mounted supporting shaft provided with a fuel feed channel, means for 10 rotating said shaft and for forcing fuel oil into the channel thereof under pressure, an atomizing cup carried by one end of said shaft and into which the fuel oil is forced under pressure, a deflector cone surrounding 15 said cup in spaced relation thereto and mounted on said shaft to rotate therewith, a housing surrounding said cone and supporting the outer end thereof, and means for supplying air under pressure into said 20 housing.

2. A rotary spray burner comprising a rotatably mounted supporting shaft provided with a fuel feed channel, means for 25 rotating said shaft and for forcing fuel oil into the channel thereof under pressure, an atomizing cup carried by one end of said shaft and into which the fuel oil is forced under pressure, a deflector cone surrounding 30 said cup in spaced relation thereto and to and adjustably mounted for movement longitudinally thereof, a housing surrounding said cone and supporting the outer end thereof, and means for supplying air under pressure into said housing.

3. A rotary spray burner comprising a rotatably mounted supporting shaft provided with a fuel feed channel, means for 35 rotating said shaft and for forcing fuel oil into the channel thereof under pressure, an atomizing cup carried by one end of said shaft and into which the fuel oil is forced under pressure, a deflector cone surrounding 40 said cup in spaced relation thereto and mounted on said shaft to rotate therewith, said cone being capable of longitudinal 45 movement on said shaft for adjustment relatively to said cup, a housing surrounding said cone and supporting the outer end thereof, and means for supplying air under 50 pressure into said housing.

4. A rotary spray burner comprising a fan casing provided on its opposite faces with air inlet and discharge openings, a

rotatably mounted fuel supply shaft extended through said casing, means for 55 rotating said shaft and for supplying fuel thereto under pressure, a fan positioned in said casing and carried by said shaft, a cupped housing extending from the discharge opening of said casing, an open 60 ended deflector cone carried by said shaft and supported at its outer end by said housing, and an atomizing cup within said deflector cone and rotatably carried by said 65 shaft.

5. A rotary spray burner comprising a rotatably mounted supporting shaft provided with a fuel feed channel, means for 70 rotating said shaft and for forcing fuel oil into the channel thereof under pressure, an atomizing cup carried by one end of said shaft and into which the fuel oil is forced under pressure, an open ended deflector cone surrounding said cup in spaced relation thereto, a housing surrounding said cone, 75 and means for supplying air under pressure to said housing.

6. A rotary spray burner comprising a rotatably mounted atomizing cup, means for 80 rotating said cup and for supplying fuel oil thereto under pressure, an open ended deflector or incasing said cup in spaced relation and capable of longitudinal movement relatively thereto, an open ended housing surrounding 85 said deflector, and means for supplying air under pressure into said deflector.

7. A rotary spray burner comprising a rotatably mounted supporting shaft provided with a fuel feed channel, an atomizing cup at one end thereof, means for rotating 90 said shaft, a pump for supplying fuel oil under pressure to said shaft, a geared connection between said shaft and pump, a housing inclosing said geared connection, a fuel supply connection from said pump to 95 said gear housing, and fuel inlet connections provided in said shaft and connecting the interior channel thereof with said housing.

In testimony whereof I have signed my 100 name to this specification in the presence of two subscribing witnesses.
